Warren G. Ogden

UNITED STATES PATENT OFFICE

THEODORE WILLIAM MONROE, OF BROOKLINE, MASSACHUSETTS

TOBACCO POUCH

Application filed September 8, 1927. Serial No. 218,207.

This invention relates to tobacco pouches, and more particularly to flat tobacco pouches having provision for humidifying the tobacco therein.

5 In using flat tobacco pouches consisting merely of a two-walled casing, the tobacco dries out quickly and when in such condition becomes practically unusable. The condition of the tobacco deteriorates also by being shaken up in the pocket of the user causing a grinding action of the walls of the pouch which is transmitted directly to the tobacco which, if in a dry condition, pulverizes very quickly and is then useless for a pleasant smoke. However, if the tobacco is maintained moist the grinding and pulverizing action is minimized and smoking such tobacco is soothing and desirable. Several methods have been proposed for maintaining 15 tobacco carried in a pouch in a moist condition but, as far as I have been able to determine, none have been commercially successful.

The objects of this invention are to provide 20 a flexible wallet-type pouch having provision for humidifying the tobacco therein, which may easily and cheaply be made and yet not be cumbersome; to provide for a continuous addition of moisture for humidification in a 25 simple and convenient manner; to provide a pouch of this character in which the moist absorbent material used is separated from the tobacco so that it is merely humidified and not soaked; to provide in a wallet-type pouch 30 certain reinforcements which assist in preventing deformation of the pouch and thus promoting successful humidification; and generally to improve the art of making 35 pouches of the type described.

40 To the accomplishment of these objects and such others as may hereinafter appear, as will readily be understood by those skilled in the art, the invention comprises the features 45 and combinations of elements hereinafter described and then particularly pointed out in the appended claims.

The features and scope of the invention will best be understood from a description of 50 the preferred embodiments thereof illus-

trated in the accompanying drawings, in which:

Figure 1 is a view, in perspective, of the improved pouch showing the flap open;

Fig. 2 is a view, in perspective, of a section 55 of the pouch shown in Fig. 1;

Fig. 3 is a view, in elevation, of the lining of the pouch shown in Fig. 1 with the lining flap open; and

Fig. 4 is a view, in section, of a modified 60 form of the improved pouch.

Referring first to Figs. 1 to 3, the flat pouch illustrated consists of a casing, generally indicated by the numeral 1, made up of two pieces of flexible sheet material stitched together at three edges, as shown at 2, to provide a mouth. The back wall 3 in the illustrated form extends beyond the front wall 4 to form a closing flap 5, which may be provided with suitable snap fasteners such as 6 65 to hold it in closed position as seen in Figs. 2 and 4, the casing being the same in the modified form shown in the latter figure. It is within the scope of the invention to employ 70 other means for closing the mouth of the pouch, the invention being equally advantageous regardless of the type of closure used. 75

The lining member 7 is shown detached from the casing in Fig. 3 and is preferably being made up of a front member 8 and a 80 back member 9, the latter being extended upwardly to form a flap 10. The lining, except the flap 10, is usually cemented to the inside of the casing 1, although this is not essential since securement is usually obtained by 85 stitching to the casing, as shown at 11, about the mouth of the pouch. The parts thus far described are the usual construction of wallet-type pouch as at present obtainable.

It is desirable, especially when using a 90 humidifying agent, to reinforce the pouch in a manner to retain the bottom of its walls in an extended position to hold the tobacco loosely and prevent powdering as far as possible. For this purpose I insert a channel-shaped member 12 that is preferably, but not necessarily, fixed to the lining 7 at the bottom thereof to keep it in open position with its walls apart, as shown in Fig. 2. Obviously 95 the same result is obtained if the member 12 100

is secured within the casing 1, and the lining then secured to it by cement, or by any other suitable means.

For the purpose of humidifying the tobacco in the pouch I provide a pocket for receiving moist absorbent material that is separate from the pocket which receives the tobacco. This humidifier pocket is formed by attaching an auxiliary member 13, which 5 may conveniently be of the same material as the lining, as by stitching it on three edges to one wall of the lining member 7. The pocket thus made is adapted to receive absorbent material such as a sheet of blotting paper 14 which is first moistened with water. Until dried out evaporation will humidify the tobacco.

The preferred location of the humidifier pocket, either on a wall of the lining (Figs. 20 and 3), or on a wall of the casing (Fig. 4), is such that its mouth lies along the line of the opening, or mouth, of the pouch. This location affords easy access to the humidifier pocket when necessary for replenishment of 25 the humidifying agent. With this form of the invention it is important that, in opening the mouth of the pouch, the humidifying pocket be surely moved bodily with the wall against which it lies, away from the opposite 30 wall. In other words provision should be made to insure that the pocket will not be opened or torn during the frequent opening of the pouch to gain access to the tobacco therein. Accordingly the free edge of the 35 material 13 is reinforced throughout its length by running a flexible wire 16 through a hem 17. This stiffens the material at one side of the mouth of the pocket and causes it normally to lie snugly against the other 40 side, but an additional fastener, such as the snap 15, may be used if desired.

A further important advantage of reinforcing the mouth of the humidifier pocket is that it provides a stiffened edge to the 45 mouth of the pouch that, however, may readily be bowed outward and when so bowed merely by pressure from the thumb at its center will, because of its length, maintain the pouch mouth fully open for the introduction of the bowl of smoker's pipe. Likewise the wire 16 can be as easily bowed inward, 50 away from the pouch wall 4 (see Fig. 1), to open the humidifier pocket when required.

The flexible nature of the stiffener permits 55 it always to straighten out when the pouch is closed. In addition, the stiffener element serves to retain the pouch in an extended position and thus prevents to some extent at least the pulverizing of the tobacco if it 60 gets dry.

The modified form of pouch shown in Fig. 4 is the same as that above described, with the exception that the lining member 7 is omitted and the auxiliary member 13 which 65 forms the humidifier pocket is attached di-

rectly to the wall of the casing 1. In the event that the casing is made of some water impervious material, such as rubber or oil cloth, this form is desirable.

It will be observed that it is important that the moistener-pocket shall be affixed to the outer wall of the pouch and that it shall be so attached thereto that, when the outer wall is forced away from the back wall to thus open the tobacco-receptacle, the moistener-pocket shall follow this front wall and thus avoid interfering with filling the pipe by dipping it into the pouch. It is also important that the moistener-pocket and the closure device thereof, when said device is closed by normally-closing means, shall flex with the outer wall when said outer wall is sprung to open position, which position is shown in Fig. 1.

While I have shown and described but two forms of my invention, it is obvious that changes may be resorted to within the skill of the artisan without departing from the spirit and scope thereof as defined by the appended claims.

What is claimed as new, is:

1. The combination with a flexible tobacco pouch having a closure-flap, of a moistening device embodying a sheet of flexible fabric fastened to the inner face of the outer wall of said pouch to thus form a pocket, the upper edge of said fabric being disconnected from said outer wall to thus form a mouth for said pocket, and flexible closure means for the mouth of said pocket embodying a flexible wire in said upper edge, for the purpose set forth.

2. The combination with a flexible tobacco pouch having a closure-flap, of a moistening device embodying a sheet of flexible fabric fastened to the inner face of the outer wall of said pouch, the upper edge of said fabric being disconnected from said outer wall to thus form a mouth for said pocket, and closure means for said pocket, for the purpose set forth, said closure means embodying an elastic wire fastened to the upper edge of said fabric and normally sprung toward the outer wall of the pouch to thus keep said pocket normally closed and yet permit the pocket and its closure device to flex with the outer wall of the pouch.
